UNITED STATES PATENT OFFICE.

CHARLES WESLEY McCAIN, OF VANCOUVER, CANADA.

DESIGN FOR A MEDAL.

SPECIFICATION forming part of Design No. 22,300, dated **March 21, 1893.**

Application filed January 6, 1893. Serial No. 457,551. Term of patent $3\frac{1}{2}$ years.

To all whom it may concern:

Be it known that I, CHARLES WESLEY McCAIN, a subject of the Queen of Great Britain, residing at Vancouver, Province of British Columbia, Canada, have invented and produced a new and original Design for Medals, of which the following is a specification.

In the drawings:—Figure 1, shows one face of the medal. Fig. 2, is a view of the other face.

- o The leading feature of my design is the illustration of a vessel under sail on a body of water, on one side of the medal, and a wrecked vessel on the opposite side.

The medal is circular in plan and upon the

side A, a vessel *a* is shown in a body of water *b*, under full sail. Below the picture is a crescent shaped panel which offers space for any suitable words. On the opposite face B, is a picture of a wrecked vessel while below the picture is a crescent shaped panel to contain any suitable words.

What I claim is—

The design for a medal as herein shown and described.

CHARLES WESLEY McCAIN.
